THEODORE RUSSELL, OF NAUGATUCK, CONNECTICUT, ASSIGNOR TO THE JOHN M. RUSSELL MANUFACTURING COMPANY, OF NAUGATUCK, CONNECTICUT, A CORPORATION OF CONNECTICUT.

SHOE CLASP.

Application filed May 31, 1923. Serial No. 642,521.

To all whom it may concern:

Be it known that I, THEODORE RUSSELL, a citizen of the United States, residing at Naugatuck, county of New Haven, State 5 of Connecticut, have invented a new and useful Shoe Clasp, of which the following is a specification.

This invention relates to a buckle or clasp, especially such as are used for shoes 10 and arctics, and has for an object to provide an improved clasp which may be manufactured at lower cost than those now generally employed, which will have a smoother and easier operation, which will 15 be less liable to break, will lie flatter on the fabric of the shoe and so will not cause pressure of the fabric on the foot, and which will not be as liable to cut the securing loops as will the old form.

With the foregoing and other objects in view, I have devised the construction illustrated in the accompanying drawing, in which—

Fig. 1 is a front elevation of a portion 25 of a shoe or arctic showing my improved buckle or clasp attached thereto.

Fig. 2 is a transverse section thereof, showing the clasp closed.

Fig. 3 is a similar view showing the 30 clasp open.

Fig. 4 is a bottom plan view of the clasp in open position.

Fig. 5 is a top plan view thereof in closed position.

Fig. 6 is a bottom plan view in closed position, and

Fig. 7 is a longitudinal section and front elevation of an improved form of ladder.

In the drawing 10 represents a portion 40 of a shoe or arctic closed at the front by a flexible tongue or bellows portion 11. To the opposite sides of this portion of the shoe are secured one or more buckles in the usual manner, as by threaded loops 12 45 stitched to the shoe.

As is usual, this type of securing means comprises a ladder 13 provided with a series of spaced rectangular openings 14 for entrance of the tongue or lever 15. This 50 ladder is preferably made of sheet metal and curved to correspond with the contour of the shoe and has an opening 16 for the securing loop 12. In stamping this member three sides only of the opening 16 is

cut leaving the metal attached to the body 65 at the outer edge, and the tongue 17 thus formed is then bent backwardly on the body giving a double thickness and a round edge 18 on the side of the opening which is engaged by the loop 12. It will be apparent 60 that this round edge will be much less likely to cut the loop than would the sharp edges which would be left if the metal filling the opening were entirely removed, as is the ordinary construction. 65

The other portion of the clasp or securing means comprises a frame made of wire and the tongue or lever 15 hinged thereto. In the specific construction shown this frame comprises a single piece of wire, 70 preferably round, and bent substantially the shape illustrated. In the specific form illustrated the wire is bent on opposite sides of a mid-section or bar 19 to provide spaced side members 20 extending laterally 75 from the mid-section or connecting bar 19 in the same direction, and are preferably substantially parallel. At a suitable distance from the bar 19 they are bent inwardly toward each other to provide re-entrant portions 21, and then at a suitable 80 distance from the side members are bent backwardly toward the bar 19 to provide intermediate members 22, preferably substantially parallel with the side members, 85 and at a short distance from the back bar 19 are bent upon themselves, as shown at 22', and then extend forwardly again to form resilient tongue members 23 which terminate beyond the re-entrant portions 90 21. This is the simplest form of frame, but in Fig. 6 I have shown a slightly different construction in which the side members 20' are provided with offsets or loops 95 24 a short distance from the back bar 19 to prevent the loops 12 sliding around onto the side members, as it might do in some cases in the first form if the loop should be made too large. Otherwise the frame shown in Fig. 6 is the same as that shown 100 in Fig. 4.

Hinged to the re-entrant portions 21 is the tongue or lever 15, preferably made of a piece of sheet metal, with a substantially flat back portion 25 and a front or tongue 105 portion 26 which is adapted to extend through the openings 14 in the ladder 13 in closing the clasp. This tongue portion is

secured to the back by a curved portion or loop 27, and when stamping this member the back is provided with lugs 28 on the opposite sides thereof which are adapted to be bent around the re-entrant portions 21 of the frame to hinge the lever thereto, and in forming this connection these lugs are folded outwardly so as to leave the back of the lever substantially flat. Between these hinge lugs the back is provided with a projection or tongue 29 extending beyond the axis of the hinge or pivot, as shown in Figs. 4 and 6, and is so positioned that its free end may be engaged by the tongue members 23, with which it coacts to hold the lever in open and closed positions. For the purpose of preventing the tongue members 23 sliding off this projection, its free edge is preferably provided with notches 30 in which these members may rest. It will thus be apparent that, as the free edge of the tongue 29 projects beyond the axis of the pivot for the lever, when the lever is turned on its pivot to the open and closed positions the free edge of the tongue 29 will move through an arc of a circle and press the tongue members 23 laterally, but the tongue will be substantially parallel with these members with its free edge on opposite sides of the pivot when the lever is opened and closed, and the pressure of these resilient members thereon will tend to hold the lever either in the open or the closed position.

There are several distinct advantages of this construction of clasp over the old form of sheet metal clasp. As the frame is made of wire it may be bent to shape on automatic machinery and there is no loss of material, and thus no scrap. Due to the peculiar shape of the frame the tongue members 23 have a length substantially equal to the length of the frame, and so they are much longer than the tongue of the sheet metal frame, and, therefore, give a much smoother working and more easily operated lever than is secured with the sheet metal frame, and furthermore, it is not so liable to break under continued operation. There is also less friction and less liability of rapidly wearing out. Furthermore, in this construction the folded ears or lugs 28 may be formed on the lever which does not require to be tempered as does the frame of the old type of construction made of sheet metal. As the formation of these ears require a sharp bend in the material, the sheet metal frame must be made of soft annealed metal as otherwise the lugs or ears would be broken off in bending, and then the frame must be tempered to give a resilient action to the tongue. With the present construction these lugs are formed on the lever which does not require to be tempered. They may also be bent outwardly, as shown, so as to give a substantially flat back 25 with no projections press-

ing against the fabric of the shoe or against the foot of the wearer and, therefore, are more comfortable. This flat back, also, as shown in Fig. 2, when the lever is closed lies flat against the surface of the fabric, and so assists in holding the lever in closed position. Still further, as the pivot lugs or ears 28 are wrapped around the re-entrant portions 21 between the side members 20 and intermediate members 22, they hold the frame together preventing it from spreading or opening sidewise thus making a much more rigid frame. Furthermore, as the frame is preferably made of round wire it is much less likely to cut the loop 12 than are the sharp edges formed when the opening for this loop is stamped from a piece of sheet metal. The frame may be made either of resilient or spring wire, or a soft wire which can be tempered after the frame has been bent to give the spring action for the tongue members 23. This construction also eliminates one operation required in forming the tongue when it is used with a sheet metal frame. In this old form of construction the body plate or frame is of high carbon steel while the lever or tongue is of low carbon steel, and as the whole buckle after assembly has to be heated in tempering the body, this anneals the tongue or lever at the same time, and it is, therefore, necessary to provide a corrugation to reinforce and give the necessary strength to the tongue or lever. This is not necessary with the present form. In the present construction there is not as much danger of the tongue or lever breaking or cracking as in the old form, as no heating and tempering operation is required.

Having thus set forth the nature of my invention, what I claim is:

1. In a clasp, a wire frame having re-entrant sides bent backwardly and then upon themselves to form a resilient tongue, and a lever hinged to said frame and provided with a tongue coacting with the frame tongue to hold the lever in closed position.
2. In a clasp, a wire frame having a longitudinally extending resilient tongue, and a lever hinged to the frame and provided with a projection extending beyond the hinge and terminating in a free edge engaged by said tongue.
3. In a clasp, a frame comprising a wire with the sides on opposite sides of its mid-section extending laterally in the same direction, then extending inwardly toward each other for a short distance, then longitudinally toward the mid-section and then bent back upon themselves to form a resilient tongue, and a lever hinged to the inwardly extending portions and provided with a tongue coacting with the frame tongue to hold the lever in different positions.
4. In a clasp, a wire frame comprising

spaced side members connected to a transverse bar at one end adapted to engage a securing loop, said side members extending inwardly toward each other at their opposite ends, then longitudinally of the frame toward said bar and then inwardly toward each other and backwardly toward the other end of the frame to provide a resilient tongue, and a lever pivoted to the frame at the latter end and provided with a free edge at one side of the pivotal axis adapted to engage said tongue whereby the lever is held in closed position.

5. In a clasp, a wire frame having re-
entrant sides bent backwardly and then upon themselves to form a resilient tongue, and a lever hinged to said frame and provided with a tongue having a free edge coacting with the frame tongue to hold the lever in closed position, said free edge being provided with one or more notches to receive the wires of said tongue to hold them in proper position.

6. In a clasp, a wire frame comprising

spaced side members connected to a bar at 25 one end adapted to engage a securing loop, said side members being provided with inwardly extending offsets a short distance from said bar to prevent the loop moving around onto the side members, said side 30 members extending inwardly toward each other at the other end of the frame and then bent to form a resilient tongue, and a lever pivoted to the frame on said inwardly extending portions and provided with a free 35 edge at one side of its pivotal axis and adapted to coact with said tongue to hold the lever in different positions.

7. In a clasp, a frame having transversely extending portions, and a securing lever 40 having a substantial flat back portion and provided with ears folded outwardly from the plane of said back portion over said transversely extending portions to hinge the lever to the frame.

In testimony whereof I affix my signature.

THEODORE RUSSELL.
